MULTIPOSITION ELECTRIC SWITCH

Robert H. Bentley and Walter L. Dietrich, Hartford, Conn., assignors to The Arrow-Hart & Hegeman Electric Company, Hartford, Conn., a corporation of Connecticut

Application November 8, 1939, Serial No. 303,472

34 Claims.

(Cl. 200—78)

This invention relates to electric switches. More particularly it relates to electric snap switches of the type in which the movable contact is capable of occupying more than two positions. In switches of this type as heretofore made, the handle and mechanism could quickly be run, inadvertently or purposely, in either direction through a second position into a third, without stopping in the second position, although the purpose of the person operating the switch might not be to go from the original position to the third position immediately.

Under some conditions, the failure to stop or the ability to move directly through the second position is highly objectionable.

Under other conditions, it is desirable to have a multiposition switch, for example a three-position switch, in which the movable contact, when moving in one direction, may snap through the mid-position while moving from one extreme position to another, but when moving in the opposite direction the movable contact will be compelled to halt before moving onward into its extreme position. The same may apply if the switch is to occupy more than three positions.

In a three-position switch of this type, it may also be desired that the contact-operating-member be incapable of movement from an intermediate position back into an extreme position out of which it has just moved, as for example in a motor starting switch, where provision must be made against throwing the switch from "off" position directly into "running" position without first moving into "starting" position.

Under still other conditions, it is desirable to have a three-position switch in which the movable contact will remain in one of its extreme positions only when the operating lever is manually held, but in other respects will operate normally and be prevented from snapping through mid-positions without halting. In this case also the desired object may extend to switches in which there are more than three positions of rest.

It is an object of our invention to provide an improved form of an electric snap switch in which the mechanism can be moved into more than two positions and in which it is impossible to go from one position to the second succeeding position without stopping in the next succeeding or intermediate position.

Another object is to provide a multiposition switch in which, when the contact-operating-member is moved in one direction, it is impossible for it to go from a given position to a second

succeeding position without stopping in the next (first) succeeding position, but when the contact-operating-member is moved in the opposite direction, it can be moved through an adjacent position without stopping.

Another object is to provide a multiposition switch in which, when the contact operator moves in one direction from one position to another, it is compelled to stop in the second position before continuing onward into a third position, but when the contact operator moves in the opposite direction, it will skip freely through a second position into a third.

Another object is to provide a three-position switch in which, (1) when the contact operator moves in one direction from an extreme position, it is impossible for it to go to the other extreme position without stopping in the intermediate position; (2) when it moves in the other direction, it will skip through the intermediate position without stopping; and (3) when it has moved into intermediate position, it cannot be returned directly to the extreme position from which it has just come.

Another object is to provide a multiposition switch in which the contact operator can only move into its several positions in sequential order.

Another object is to provide a multiposition switch in which a movable contact will remain in one position only when manually held there but in which the movable contact can be moved into said position through an adjacent position from a third position only after the movable contact has halted in said adjacent position; and, conversely—as another object—when said movable contact is moved from the position in which it was manually held, it will be halted in an adjacent position in spite of an attempt to move through said adjacent position to a third position without a halt.

Another object of our invention is to provide an effective and rugged construction of multiposition electric switches of the above and related types which can be made with a minimum of expense and labor.

Other objects and advantages of our invention will become apparent as it is described in connection with the accompanying drawings.

This application is a continuation-in-part of our application, Serial No. 106,923, entitled "Three position electric switch," filed October 21, 1936.

In the drawings—

Fig. 1 is a top plan view of our new improved

construction of three-position electric snap switch with the cover and operating handle removed.

Fig. 2 is an exploded perspective view of the main parts of the switch operating mechanism.

Fig. 3 is a longitudinal section view taken vertically through the invention along line 3—3 of Fig. 1.

Fig. 4 is a longitudinal section view taken vertically through the invention along line 4—4 of Fig. 1.

Fig. 5 is a transverse or cross-sectional view of the invention taken along line 5—5 of Fig. 1.

Fig. 6 is a longitudinal sectional view taken vertically through the operating mechanism of our invention and taken along line 6—6 of Fig. 1.

Fig. 7 is a side elevation view of a modified form of motion-limiting mechanism which forms a part of our invention.

Fig. 8 is an end elevation view of the construction shown in Fig. 7.

Fig. 9 is a longitudinal section view partly broken away, with the section being taken in a plane, such as is indicated by line 9—9 of Fig. 1, but of a modified form of the invention.

Fig. 10 is a detailed side elevation view of the operating mechanism of the switch of Fig. 9 with the parts being restrained from moving through mid-position without stopping.

Fig. 11 is a fragmentary detail view of the switch of Figs. 9 and 10 with the parts in mid-position.

Fig. 12 is a view similar to Fig. 10 but of a third form of the invention.

Figs. 13-15 are diagrammatic views of the operating mechanism of the third form of invention, in various positions.

Fig. 16 is a detail view of the handle and cam member used in the third form of invention.

Referring to the drawings, the parts of the switch in all forms of the invention are mounted within a rectangular insulating base 10 which is hollowed out centrally for the reception of switch operating mechanism, the hollowed out part or recess in the base having parallel endwise extensions (see for example 11 and 13) into each corner of the base giving the recess an H-formation. One each of four identical stationary wire terminal members 12, 14, 16 and 18 are mounted in each of the four corners of the casing at the end of the aforementioned endwise extensions, these terminals preferably being slipped into vertical slots formed in the walls of said extensions. These terminals, 12 for example, are each stamped from sheet metal into right angular formation with one arm 12^a, shorter than the other, the short arm having a binding screw 12^b threaded therein and accessible through an aperture in the bottom of the base 10. Resilient contact fingers 12^c, 14^c, 16^c, 18^c are riveted to the upper ends of the longer arms, for example 12^d, of the terminals and extend toward the middle of the base. In the middle of the base at opposite sides of the recesses therein are combination terminal and stationary contact members of tridentate form, designated generally by the numerals 20 and 22. These members 20, 22 may be identically formed and fabricated of two elements: one, a contact element, being of resilient metal stamped into U-shape with the end portions 20^a, 20^b functioning as contact fingers; the other 20^c, a terminal element, may be stamped from sheet metal in a form like 12, 14, 16 and 18. These elements of the members 20 and 22 are riveted together with the bridge portion of the U across the center of the long leg of the ter-

5 minal, the ends of the resilient contacts 12^c and 20^a being of size and position to be opposite to each other and likewise will also the end portions of resilient contacts 20^b and 14^c, 22^b and 16^c, 22^a and 18^c be opposite. In order to bridge the pairs of contacts 20^a, 12^c and the resilient contact fingers 20^b and 14^c (and in like manner contacts 16^c, 22^b, 18^a and 22^a) movable contacts 24 and 26 are provided. These movable contacts 10 are of sheet metal stamped into the shape of a U with its ends inturned. The contacts are mounted on sheet insulation slides 28 and 30 at the center of the top edges of the slides in position to engage, in extreme positions, the aforementioned contact pairs. The slides ride on the floor of the base parallel to the side walls and between the faces of the aforementioned contact pairs in the manner illustrated most clearly in Figs. 1 and 5 of the drawings.

20 In order to move the slides in unison there is a pin 32 extending transversely of the base and engaging in recesses 31 in the slides adjacent their bottom edges. This pin 32 is caused to oscillate by switch operating mechanism in such a manner that the pin may occupy a mid-position, as shown in Figs. 1 and 3, and two extreme or end positions, the right end position being shown in Fig. 6 and the left in Fig. 9.

In all forms the mechanism for operating the switch contacts is mounted upon a frame comprising a pair of parallel side plates 33 and 34 which are connected at their ends by narrow plates 36 and 38 in a conventional fashion. The mechanism in Figs. 1-8 is operated by an operating lever 40 which is pivoted by a pin 42 positioned diametrically in a metallic nipple 44 mounted centrally in a plate 46 that extends over the top of the switch base 10 and has between it and the base a centrally perforated insulating plate 48. The plate 46 may be secured to the base by through-bolts 50. The end of the operating lever 40 which extends within the casing has a number of gear teeth formed on it to engage with similarly cut teeth on an operating cam plate 52. This operating cam may be a flat sheet metal stamping of approximately triangular shape, being rotatably mounted at its apex upon a spindle 54 which in turn is mounted transversely between the side plates of the switch frame. It may now be seen that due to the engagement of the teeth on the operating cam 52 and the operating lever 40 the cam may be rotated about spindle 54 into various positions. The bottom edge of the operating cam 52 has a cam surface upon it having arcuate portions 52^a, 52^b and a central depressed portion or notch 52^d. When the switch is at rest the operating pin 32 seats in the notch 52^d.

60 In order that the operating pin 32 and hence the movable contacts may move with a snap motion, means are provided to keep the movement of the operating handle from being immediately and directly transmitted to the operating pin 32. Thus in the center of the operating cam 52 a strut 56 is positioned by providing a T-shaped aperture in the cam and providing notches in the side of the strut so that the strut may be moved up into the small part of the aperture 52^c. A pair of wire springs 58 are coiled around the spindle 54 on opposite sides of the operating cam and the ends of these springs engage opposite sides of the strut 56. The ends of these springs also engage opposite sides of lugs 60 struck out from a fabricated oscillating switching member, which is designated generally by

the numeral 62. This switching member is formed of identical sheet metal stampings 64 and 66 having the configuration as may best be seen in Figs. 2 and 6. The upper portions of these stampings are positioned on opposite sides of the operating cam 52 while the lower portions are offset and are secured together by a bracket 68 which has apertures adjacent its opposite ends for the reception of projections 70 on the opposite end of the stampings 64 and 66. The ends of these projections are peened over to secure the stampings 64 and 66 and the bracket 68 firmly together but with the stampings far enough apart to permit oscillating movement of the operating cam between the stampings.

Embraced between the lower portions of the stampings 64 and 66 is a sliding yoke 72 through the lower portion of whose arms passes the operating pin 32. This yoke is held in position between the lower ends of the stampings 64 and 66 by means of inturned lugs 74 but the yoke is permitted limited sliding movement relative to the stampings by reason of elongated slots 76 in the lower portions of the stampings 64 and 66 within which slots the end portions of the operating pin 32 work. A coil spring 78 positioned between the bottom of the yoke 72 and the bracket 68 urges the yoke upwardly and the ends of the operating pin into engagement with the top of the slots 76. The whole fabricated switching member, with the yoke mounted therein as described, is pivotally mounted upon the spindle 4.

To guide the operating pin 32 in its movement here are provided in the side plates of the switch frame identical raceways 80 which have arcuate portions 80^a intersecting adjacent a central socket 80^c and terminating in end pockets 80^b, all the pockets being in the upper surface of the raceways. A peak 80^d is formed in the middle of the lower surface of the raceways.

Assuming that the switching mechanism is in the position of Fig. 6, it may be seen that as the operating lever is moved counter-clockwise the operating cam 52 will move clockwise, its surface 52^a pushing the operating pin 32 longitudinally in the slots 76 and out of the right-hand pockets 80^b in the side plates of the switch frame. While moving the operating cam stresses the switch springs 58 which act on the fabricated switching member 62 tending to move it in clockwise direction. As soon as the operating pin 32 moves it of the right-hand pocket 80^b the switching member 62 is free to move and the stress of the switch spring moves the switching member with snap motion in a clockwise direction carrying with it the yoke 72 and the operating pin 32 and thus necessarily the slides 28 and 30 and the movable contacts 24 and 26 mounted thereon.

The operating lever is carried past its mid-position, as is quite often the case, the operating lever will likewise be carried past its mid-position and the arcuate surface 52^b will be in position to prevent the operating pin 32 from coming to the central pocket 80^c of the raceway. At this time the pin 32 will be in position X of Fig.

Thus the switch contacts will be held substantially in mid-position and will not be able to pass into an extreme position opposite to that in which they have just departed until the handle and operating cams come into their mid-situations, thereby placing the center notch 52^d of the cam and the center pocket 80^c of the plate in registry and permitting the operating pin 32 to move therein. After this has been accom-

plished the operating lever may be moved in either direction so that either cam surface 52^a or 52^b will engage pin 32 and move it out of notch 80^c to permit the movable contacts to go into either extreme position as may be desired.

The trivial movement of the movable contacts which may result from the operating pin 32 not being able to immediately fully enter the pockets 80^c in the case of over-travel of the handle, is of no importance in the switch illustrated for the reason that the central position is an open-circuit position. However, if it is desired to have the central position a circuit-making position a modified form of stop or over-travel preventing means, as illustrated in Figs. 7 and 8, may be provided.

In this form of the switch the operating mechanism is identical with that just described but the peak 80^d is omitted from the raceway in the side plates of the switch frame, in fact the whole lower surface of the raceway is removed and a similar peak 106 is formed upon an additional or auxiliary plate 100 which is substantially in the form of a hollowed out segment. The auxiliary plate is mounted upon the spindle 54 and is permitted limited oscillating movement so that when the pin 32 strikes the peak 106 it will carry that peak and the auxiliary plate 100 slightly away from its center position. This will allow the pin 32 to come into mid-position at once and be ready to move up into the pocket 180^c whenever the notch 52^d in the operating cam comes in registry with pocket 180^c. It may be noticed that the pin cannot travel at once over the peak 106 into the arcuate portion 180^a of the raceway because the peak and the surface 52^b of the operating cam do not afford enough clearance for the pin to pass between them. Stop lugs 107 may be struck from the side plate 134 to limit the movement of the auxiliary plate 100. In order to hold the auxiliary plate normally in mid-position the spindle 54 may be extended far enough through the side plates of the frame to permit a spring 108 to be coiled around the extended end. The ends of the spring will be engaged with the opposite sides of a fixed lug 110 struck out from the frame plate 134 and movable lug 112 formed on the auxiliary plate.

To shield the operating parts from the play of any arc between the contacts, vertical plates 90 of insulation may be interposed between the contacts and mechanism in the position shown in Figs. 1 and 5.

Referring now to Figs. 9-11, wherein another form of the invention is shown, the operation in this form is similar to that just described in connection with Figs. 7 and 8 except that on moving the contacts into the extreme right position, they will not remain there unless the operating handle is held manually in the extreme left position.

In this form, the gear connection between the handle and operating member, as shown in Fig. 3, is omitted and handle 240 (see Figs. 9 and 10) has the cam member 252 rigidly connected thereto. In this form the cam member may be made of two identical plates which are placed back-to-back with their upper ends embedded in the molded composition handle 240. A flange 252^a is turned at right angles to the lower end of each plate forming a cam surface having a profile similar to that of cam plate 52 of Fig. 2. Switching member 62 of Figs. 1-6 has its counterpart in Figs. 9-11 in a one-piece, stamped, sheet-metal, U-shaped switching member 262,

with ears 268 bent up from the transverse bottom portion, in planes perpendicular to the sides of the switching member, thus forming a pocket for the spring 18. Spring 18 presses operating pin 32 upward in slots 76 for the same purpose as in the form of Figs. 1-6.

In lieu of the oscillating auxiliary plate 100 of Figs. 7 and 8, the form of Figs. 9-11 employs a reciprocating stop member 200 composed of a pair of identical plates which are connected by transverse bars adjacent the plate ends, the member being stamped from sheet metal into U-shape. The ends of the side plates of the stop member 200 are equally slotted as at 203 to accommodate guide pins 204 which are positioned transversely in the frame, having their ends secured in the frame plates 233, 234.

For the purpose of maintaining the stop member 200 in a certain central position (see Fig. 11) a spring 208 is wound around one of the pins 204, with the spring ends pressing against opposite sides of a strut 210 which connects the side plates 233, 234. The spring ends also embrace a lug 212 bent in from one of the corners of the stop plate 200 (adjacent the left end in Fig. 9). Thus if the lug 212 and stop plate move to the right or left, the spring 208 will tend to return the stop member to central position.

In order that the switching member 262 shall not remain in the extreme right-hand position except when the handle is held manually in the extreme left, a spring 259 is wound around the pivot pin 254 of the switching member. One end 259^a of the spring presses against the cover 246. The other end 259^b of the spring presses against a lug 256 struck out of the cam operating member 252. The effort of the return spring 259 is adequate to move the operating handle and cam operating member to shift the switch operating member into mid-position as shown in Fig. 11 because of two factors: (1) the strength of the spring itself, which need be only strong enough to move the pin 32 along the cam surface 280^s into the pocket 280^c; (2) the surface 280^s is straight and does not terminate in a pocket as does the surface 280^a (which is equivalent to surface 80^a in Figs. 1-6) so that little effort is required to move the pin 32 from the notch 280^s formed by the intersection of the surface 280^s and the vertical surface 280^v which limits the right hand movement of the pin 32.

From the foregoing description of the parts of the form of invention shown in Figs. 9-11, as compared with the parts of the forms of the invention shown in Figs. 1-8, the operation of the form of Figs. 9-11 may be understood. When the switching member moves from the position of Fig. 9 to the right, it must halt in mid-position because the projection 206 on the stop member 200, upon being abutted by pin 32, moves to the right and prevents passage of the pin 32 (see Fig. 10) until the pin seats in pocket 280^c and releases stop member 200 (see Fig. 11). Then, on moving the switch handle to the extreme left, pin 32 is caused to move to the right pressing down on the right hand slope of the projection and moving the stop member to the left, the pin 32 thus making way for itself to move against the vertical stop surface 280^v.

As soon as one's hand is removed from the handle, the return spring 259 will move the handle into central position causing the switch parts to move also into central position (see Fig. 11).

Due to the fact that there is practically no resistance to the movement of pin 32 from notch 280^s as the handle is moved (either under the effort of the spring 259 or by manual force), the handle and switching member 262 and operating pin 32 move as a unit as the pin 32 moves from notch 280^s to mid-position.

It will be noted that in Figs. 9-11, the switch operating mechanism and contacts are capable of coming to rest in three distinct positions, although in one position manual force must be applied to the handle, to prevent the spring 259^a from moving the handle and thus actuating the operating mechanism from one of its positions.

Referring now to Figs. 12-16, the construction of the operating mechanism is generically the same as in Figs. 9-11, but differs therefrom in the shape of the cam operating member 352 in order to require movement of the switch into its positions sequentially, as hereinafter described. In function, Figs. 12-16 differ from the other forms of the invention, firstly in the respect that in moving from right to left, the pin 32 normally snaps through mid-position without a stop, although the switch mechanism must halt in mid-position as the operating pin 32 moves from left to right as in all the other forms of the invention. The switch parts will remain in all of the three positions without manual assistance. Secondly, when the pin is in mid-position, it cannot be moved back to the left end-position but it must go into the right end-position first, and only then can it be moved into the left end-position, skipping through mid-position on the way.

In structure, the stop member 302 of Fig. 12 differs from similar stop member 202 of Figs. 9-11 in that slot 303^a at the left end of said member is of less length than the slot 303^b at the right end (which is the same length as slot 203 of Figs. 9-11). Also the right surface of the projection 306^a and the left surface of the pocket 380^c are so formed that when the pin 32 hits the right side of the projection (in moving from right to left) and carries the stop member 302 to the left until the end of slot 303^a abuts the cross pin 208, there will still be room enough between the surfaces of the stop member and the adjacent surfaces of the frame to permit passage of pin 32. Hence pin 32 will not be halted in mid-position in passing from right to left. To facilitate the pin skipping through center in going from right to left, the left surface of pocket 380^c may be inclined, as illustrated in Fig. 12, so as to reduce friction and facilitate movement of the pin across the surface out of the pocket and into the next position. The spring for causing the snap movement of the contacts should be made strong enough to cause the pin to carry through mid-position by its own momentum, even though the handle has been moved only normally and has not been caused to over-travel substantially.

On the other hand, pin 32 will be halted in passing from left to right because the left surface of projection 306^a and the right surface of pocket 380^c are the same as in Fig. 10, and slot 303^b is the same as 203.

Switches of the type of Figs. 12-16 find a wide field of use in starting motors. In such case, the extreme right position of pin 32 (when located in notch S as in Fig. 14) is the "starting" position and the extreme left position (with pin 32 in notch R) is the "running" position. Mid-position (as shown in Fig. 12) is the "stop" position.

In order to make it impossible to move the switch into "running" position, directly from "stop" position, we cut away the right surface 352^a of the cam operating member, from the center toward the right end (see Fig. 16) sufficiently to prevent that surface of the cam from moving the pin 32 out of the pocket 380^c when the handle 240 is moved to the right (see Fig. 13). Thus, the handle will abut the right end of the slot in the casing cover 348, through which the handle projects, and will be halted, as shown in Fig. 13, before the cam surface 352^a has moved the pin 32 far enough to disengage itself from the pocket 380^c. Therefore, movement of the pin 32 from mid-position (Fig. 12) to extreme left position cannot be directly accomplished. The pin must first move into extreme right-position (Fig. 14) and then skip through center to extreme left-position. The cut away portion 352^a of the operating cam does not prevent movement of the mechanism from "starting" position (Fig. 14) to "running" position because the cam and handle move through twice the arc (equal to movement through two positions) in that case that they do in moving from "stop" position (or mid-position of Fig. 12) toward "running" position. Hence the end of the cam surface 352^a comes into play and disengages pin 32 from the notch S (see Fig. 15 wherein this action has just taken place) so that the switch spring (see 58 in Fig. 6) can skip the pin 32 through mid-position to the left notch R. Operation of the pin 32 from left to right (Figs. 12-15) is normal, i. e., into mid-position and halts there, and then moves into extreme right, just as in Figs. 1-11.

From the foregoing, it can be seen that the switch of Figs. 12-16 must move sequentially through its various positions from "stop" to "starting" to "running" and back to "stop." The switch can move no other way.

If the cam surface 352^a be not cut away, the switch will then be able to operate directly from mid-position into either end-position.

From the foregoing, it may be seen that we have provided switch mechanisms which are capable of moving a movable contact into more than two positions and in which it is impossible, by over-throw of the operating handle, to move the movable contact from one position through the next position into a second succeeding position without stopping in that next or intermediate position.

We have also provided multiposition switches which prevent movement through adjacent positions when moving continuously in one direction but permit movement through adjacent positions when moving in the other direction. We have also provided a switch in which the contact operator cannot be returned directly from mid-position to the end-position from whence it came, but can be moved into that end-position only after going through each of its other positions sequentially.

It will be observed that in each of the forms of the invention, the contacts may come to rest in three distinct positions, but in one form, the handle has only two positions of rest and may be held in a third position to allow the contacts to remain in their third position of rest.

The principles of the invention are applicable to switches having more than three positions.

Many other forms within the scope of our invention will occur to those skilled in the art. Therefore we do not limit ourselves to the specific

embodiments of the invention as illustrated and described.

What is claimed is:

- 5 1. In an electric switch, fixed and movable switch contacts, means to move said movable contact into more than two positions of rest, handle means for operating the switch, and means including stationary and movable members cooperating to prevent said movable contact upon moving from one position toward an adjacent position from moving through said adjacent position without remaining therein when said handle means is made to over-travel substantially in an effort to move said movable contact through said adjacent position without stopping, the cooperation of said stationary and movable members being independent of current flow in the switch.
- 10 2. In an electric switch, fixed and movable switch contacts, means to move said movable contact into more than two positions of rest, handle means for operating the switch, and means including cooperating members at least one of which is movable and engageable by a part of said movable contact-moving means, and effective upon operation of the switch to halt said movable contact in the position of rest adjacent its starting position, when said handle means is made to over-travel substantially in an effort to move said movable contact through a position adjacent the starting position without stopping therein, the operation of said cooperating members being independent of current flow in the switch.
- 15 3. In an electric switch, fixed and movable switch contacts, means to move said movable contact into more than two positions of rest, handle means for operating the switch, and means including a member movable with said handle means upon operation of the switch to halt said movable contact in the position of rest adjacent its starting position when said handle means is made to over-travel substantially in an effort to move said movable contact through a position adjacent the starting position without stopping therein.
- 20 4. In an electric switch, fixed and movable switch contacts, means to move said movable contact into more than two positions of rest, handle means for operating the switch, fixed stop means, and means movable with said handle means upon operation of the switch and cooperating with said stop means to halt said movable contact in the position of rest adjacent its starting position in case of unlimited over-travel of said handle means.
- 25 5. In an electric switch, fixed and movable switch contacts, means to move said movable contact into more than two positions of rest, handle means for operating the switch, a projection, and means movable with said handle means upon operation of the switch and cooperating with said projection to halt said movable contact in the position of rest adjacent its starting position irrespective of the degree of over-travel of said handle means.
- 30 6. In an electric snap switch, fixed and movable switch contacts, a movable contact operating member, handle means for operating the switch, means to move said movable-contact-operating member into and out of more than two positions of rest with a snap motion, and means controlled by over-travel of said handle means to cause said movable-contact-operating means to halt in the position of rest adjacent its starting position,

whereby snapping of said movable-contact-operating means through said adjacent position, due to over-travel of said handle means, is prevented.

7. In an electric snap switch, fixed and movable switch contacts, a movable-contact-operating member, handle means for operating the switch, means to move said movable-contact-operating member into and out of more than two positions of rest with a snap motion, stop means, and means movable with said handle means upon operation of the switch and cooperating with said stop means to halt said movable-contact-operating member in the position of rest adjacent its starting position irrespective of the degree of over-travel of said handle means.

8. In an electric snap switch, fixed and movable switch contacts, a movable-contact-operating member, handle means for operating the switch, means to move said movable-contact-operating member into and out of more than two positions of rest with a snap motion including stationary means having a raceway therein, means actuated by said handle means for movement along said raceway, and means cooperating with said handle-actuated means and raceway to halt said movable-contact-operating means in the position of rest adjacent its starting position irrespective of the degree of over-travel of said handle means.

9. In an electric snap switch, fixed and movable switch contacts, a movable-contact-operating member, handle means for operating the switch, means to move said movable-contact-operating member into and out of more than two positions of rest with a snap motion including stationary means having a raceway therein, means slideable along said raceway but normally held in a position of rest at any one of certain points along said raceway, said slideable means being moved along said raceway with a snap, and means cooperating with said slideable means to halt said slideable means at one of said points adjacent its starting point when said handle means is made to over-travel substantially in an effort to move said movable-contact-operating member through a position adjacent the starting position without stopping therein.

10. In an electric snap switch, fixed and movable switch contacts, a movable-contact-operating member, handle means for operating the switch, means to move said movable-contact-operating member into and out of more than two positions of rest with a snap motion including stationary means having a raceway therein, means movable along said raceway and adapted to engage with said raceway at certain points to retain said movable-contact-operating means in its positions of rest, means on said raceway to halt said movable-contact-operating means in a position of rest adjacent its starting position when said handle means is made to over-travel substantially in an effort to move said movable-contact-operating means through a position adjacent the starting position without stopping therein.

11. In an electric snap switch, fixed and movable switch contacts, a movable-contact-operating member, handle means for operating the switch, means to move said movable-contact-operating member into and out of more than two positions of rest with a snap motion including resiliently mounted movable means, stationary means engaged by said resiliently mounted means, means in said stationary means receiving said resiliently mounted means to retain the latter in

certain positions of rest, and means operated by said handle means to release the engagement of said resiliently mounted means and said stationary means and to free said resiliently mounted means for movement into another position, and means on said stationary means to halt said resiliently mounted means in the position of rest adjacent its starting position, when said handle means is made to over-travel substantially in an effort to move said movable-contact-operating member through a position adjacent the starting position without stopping therein.

12. In an electric snap switch, fixed and movable switch contacts, a movable-contact-operating member, handle means for operating the switch, means to move said movable-contact-operating member into and out of more than two positions of rest with a snap motion including resiliently mounted movable means, stationary means engaged by said resiliently mounted means, means in said stationary means receiving said resiliently mounted means to retain the latter in certain positions of rest, and means operated by said handle means to release the engagement of said resiliently mounted means and said stationary means, and to free said resiliently mounted means for movement into another position, means on said stationary means cooperating with said releasing means to halt said resiliently mounted means in the position of rest adjacent its starting position when said handle means is made to over-travel substantially in an effort to move said movable-contact-operating member through a position adjacent the starting position without stopping therein.

13. In an electric snap switch, fixed and movable switch contacts, handle means for operating the switch, means to move said movable switch contact into and out of more than two positions of rest with a snap motion including a switch frame, movable means resiliently engaging said frame, means on said frame to receive and position said resilient movable means in certain positions of rest, means operated by said handle means to disengage said resilient means from said frame and cause movement of said movable contact into another position, and means on said frame cooperating with said disengaging means to halt said movable contact in the position of rest adjacent its starting position irrespective of the degree of over-travel of said handle means.

14. In an electric switch, fixed and movable contacts, a movable-contact-operating member, means to move said movable-contact-operating member into more than two positions of rest, handle means for operating the switch, and means normally permitting movement of a portion of said movable-contact-moving means in a predetermined path and responsive to over-travel of the handle to restrict said path and halt said movable-contact-operating member in a position of rest adjacent its starting position.

15. In an electric switch, fixed and movable contact means, means to move said movable contact means with a snap motion into more than two switch positions, at least two of which are conducting positions, handle means, and means including cooperating members at least one of which is movable and engageable by a part of said movable-contact-moving means and effective on operation of the switch to halt said movable contact means in a second switch position, which is intermediate its starting position and a third switch position, when said handle means is made to over-travel in an effort to move said movable

contact through said second position without stopping therein, said cooperating members continuing to halt said movable contact means so long as said handle is maintained in overtraveled position, and the operation of said cooperating members being independent of current flow in the switch.

16. In an electric switch, fixed and movable contact means, means to move said movable contact means with a snap motion into more than two switch positions, at least two of which are conducting positions, handle means, a fixed member, a movable member cooperating with said fixed member and having a projection movable upon engagement by a part of said movable-contact-moving means to restrict the passageway of said part and to require said movable-contact-moving means to halt in a second switch position, which is intermediate its starting position and a third switch position, when said handle means is made to over-travel in an effort to move said movable contact through said second position without stopping therein, the operation of said cooperating members being independent of current flow in the switch.

17. In an electric switch, fixed and movable contacts, contact operating means movable into three switch positions, handle means, means providing a fixed guide surface for a part of said contact operating means, means movable relative to said fixed guide surface and capable of being moved independently of said handle means and providing a movable surface engageable by said part of the contact operating means, said movable surface cooperating with said fixed surface to restrict the passage of said part of the contact operating means to require said part to halt in a second switch position, which is intermediate its starting position and a third switch position, when said handle means is made to over-travel in an effort to move said movable contact through said second position without stopping therein, the operation of said cooperating members being independent of current flow in the switch.

18. In an electric switch, fixed and movable contact means, means to move said movable contact means with a snap motion into more than two switch positions, at least two of which are conducting positions, handle means, and means including cooperating members at least one of which is movable and engageable by a part of said movable-contact-moving means and effective on operation of the handle means in one direction only to halt said movable contact means in a second switch position, which is intermediate its starting position and a third switch position, when said handle means is made to over-travel in an effort to move said movable contact through said second position without stopping therein, the operation of said cooperating members being independent of current flow in the switch.

19. In an electric switch, fixed and movable contacts, contact operating means movable into three switch positions, handle means, means providing a fixed guide surface for a part of said contact operating means, means movable relative to said fixed guide surface and capable of being moved independently of said handle means and providing a movable surface engageable by said part of the contact operating means, said movable surface cooperating with said fixed surface, but only when said handle means is moved in a certain direction, to restrict the passage of said

part of the contact operating means to require said part to halt in a second switch position, which is intermediate its starting position and a third switch position, when said handle means is made to over-travel in an effort to move said movable contact through said second position without stopping therein, the operation of said cooperating members being independent of current flow in the switch.

20. In an electric switch, fixed and movable contact means, means to move said movable contact means with a snap motion into more than two switch positions, at least two of which are conducting positions, handle means, and means including cooperating members at least one of which is movable and engageable by a part of said movable-contact-moving means and effective on operation of the switch in one direction to halt said movable contact means in a second switch position intermediate its starting position and a third switch position, when said handle means is made to over-travel in an effort to move said movable contact through said second position without stopping therein, the operation of said cooperating members being independent of current flow in the switch, and means to automatically return said movable contact means to said intermediate position upon release of said handle means.

21. In an electric switch, fixed and movable contacts, contact operating means movable into three switch positions, handle means, means providing a fixed guide surface for a part of said contact operating means, means movable relative to said fixed guide surface and capable of being moved independently of said handle means and providing a movable surface engageable by said part of the contact operating means, said movable surface cooperating with said fixed surface when said handle means is moved in a certain direction, to restrict the passage of said part of the contact operating means to require said part to halt in a second switch position intermediate its starting position and a third switch position, when said handle means is made to over-travel in an effort to move said movable contact through said second position without stopping therein, the operation of said cooperating members being independent of current flow in the switch and spring means to automatically return said movable contact means to said intermediate position upon release of said handle means, said fixed guide surface being formed to facilitate said return.

22. In an electric switch, fixed and movable contact means, means to move said movable contact means with a snap motion into more than two switch positions, handle means, and means including cooperating members at least one of which is movable and engageable by a part of said movable-contact-moving means and effective on operation of the handle means in one direction only to halt said movable-contact means in a second switch position, which is intermediate its starting position and a third switch position, when an effort is made to move said movable contact through said second position without stopping therein, and means causing said movable-contact-moving means to move through said intermediate position without stopping when said handle means is operated in the other direction.

23. In an electric switch, fixed and movable contacts, contact-operating means movable into three switch positions, handle means, means providing a fixed guide surface for a part of said

contact-operating means, means movable relative to said fixed guide surface and capable of being moved independently of said handle means and providing a movable surface engageable by said part of the contact-operating means, said movable surface cooperating with said fixed surface, but only when said handle means is moved in a certain direction, to restrict the passage of said part of the contact-operating means to require said part to halt in a second switch position, 10 which is intermediate its starting position and a third switch position when an effort is made to move said movable contact through said second position without stopping therein, said fixed and movable surfaces being constructed and arranged 15 to cause said movable-contact-moving means to move through said intermediate position without stopping when said handle means is operated in the other direction.

24. In an electric switch, relatively movable contacts, contact-moving means adapted to occupy more than two positions, at least two of which are conducting positions, means compelling said contact-moving means to halt in a second position intermediate its starting position and a third position as said handle means is moved in one direction notwithstanding that said handle means is made to over-travel in an effort to move said contact-moving means through said second position without stopping therein, and means causing said contact-moving means to skip through an intermediate position on reverse operation of said handle means.

25. In an electric switch, relatively movable contacts, contact moving means adapted to occupy more than two positions, at least two of which are conducting positions, means compelling said contact-moving means to halt in a second position intermediate its starting position and a third position as said handle means is moved in one direction notwithstanding that said handle means is made to over-travel in an effort to move said contact-moving means through said second position without stopping therein, and means permitting said contact-moving means, upon reverse operation of said handle means, to move through an intermediate position when said handle means is caused to over-travel during said reverse operation.

26. In an electric switch, relatively movable contacts, contact-moving means adapted to occupy at least three positions, means compelling said contact-moving means to halt in a second position intermediate its original position and a third position as said handle means is moved in one direction, notwithstanding that the handle means is made to over-travel in an effort to move said contact-moving means through said intermediate position without stopping therein, and means preventing reverse movement of said contact-moving means directly back into said original position from said intermediate position.

27. In an electric switch, relatively movable contacts, contact-moving means adapted to occupy at least three positions, means compelling 65 said contact-moving means to halt in a second position intermediate its original position and a third position as said handle means is moved in one direction, notwithstanding that the handle

means is made to over-travel in an effort to move said contact-moving means through said intermediate position without stopping therein, and means requiring said contact-moving means to be moved into said third position before it can be moved back into said original position.

28. A switch as claimed in claim 26, including means to cause said contact-moving means to move from all its positions with a snap motion.

29. In an electric switch, relatively movable contacts, contact-moving means adapted to occupy at least three positions, means compelling said contact-moving means to halt in a second position intermediate its original position and a third position as said handle means is moved in one direction, notwithstanding that the handle means is made to over-travel in an effort to move said contact-moving means through said intermediate position without stopping therein, and means preventing reverse movement of said contact-moving means directly back into said original position from said intermediate position, and means causing said contact-operating means to skip through an intermediate position on reverse movement of said handle means from a position beyond said intermediate position.

30. In an electric switch, relatively movable contacts, contact-moving means adapted to occupy at least three positions, means compelling said contact-moving means to halt in a second position intermediate its original position and a third position as said handle means is moved in one direction, notwithstanding that the handle means is made to over-travel in an effort to move said contact-moving means through said intermediate position without stopping therein, and means preventing reverse movement of said contact-moving means directly back into said original position from said intermediate position, and means causing said contact-operating means to skip through an intermediate position on reverse movement of said handle means from a position beyond said intermediate position.

31. A switch as claimed in claim 29, including means to cause said contact-moving means to move from all its positions with a snap motion.

32. A switch as claimed in claim 30, including means to cause said contact-moving means to move from all its positions with a snap motion.

33. In an electric switch, relatively movable contacts, contact-moving means adapted to occupy at least three positions, means compelling said contact-moving means to halt in a second position intermediate its original position and a third position as said handle means is moved in one direction, notwithstanding that the handle means is made to over-travel in an effort to move said contact-moving means through said intermediate position without stopping therein, and means requiring said mechanism to come to rest in said original intermediate and third positions in that order, as the switch is operated.

34. A switch as claimed in claim 33, including means to cause said contact-moving means to move from all its positions with a snap motion.
